Inventor,

Franklin D. Ford.

United States Patent Office.

FRANKLIN D. FORD, OF NEW BEDFORD, MASSACHUSETTS.

Letters Patent No. 70,331, dated October 29, 1867.

IMPROVEMENT IN NECK-TIES.

The Schedule referred to in these Letters Patent and making part of the same.

TO ALL WHOM IT MAY CONCERN:

Be it known that I, FRANKLIN D. FORD, of New Bedford, in the county of Bristol, in the State of Massachusetts, have invented a new and improved Device for Securing Neck-Ties, Carriage-Curtains, or any article to which it may be applicable; and I do hereby declare that the following is a full and exact description thereof, reference being had to the accompanying drawings, and to the letters of reference marked thereon.

My invention consists in a metallic spring, constructed and operating as herein shown.

Figure 1 is a view of the back side of a neck-tie with my invention attached to it.

Figure 2 is a view of my invention removed from fig. 1.

Fig. 1. A¹ is the neck-tie; B¹, my invention secured to A¹. Fig. 2 is a view of my invention removed from fig. 1. It is formed of wire, and so curved and bent as to form a kind of button-hole in the centre c².

Operation and Novelty.

The within device for securing neck-ties, etc., being constructed of wire, as herein shown, and attached to neck-ties, as represented in fig. 1, its operation and novelty may be noted. By pressing together the ends a² a² the parts at b² are sufficiently separated to allow the spring to slip on to the neck of the button. The pressure being then removed, the parts at b² spring together and the button is securely clasped in the eye c².

In this invention I do not confine myself to the form of spring set forth. It may be made in any practical form. Neither do I claim any device previously invented or patented for securing neck-ties; but what I claim as my invention, and desire to secure by Letters Patent, is—

The metallic-spring fastening, provided with fingers or ends a² and clamping parts c², as herein set forth and for the purposes specified.
